UNITED STATES PATENT OFFICE.

THOMAS SPENCER MILLER, OF SOUTH ORANGE, NEW JERSEY.

CABLEWAY BUTTON-STOP.

1,031,360.

Specification of Letters Patent.

Patented July 2, 1912.

Application filed August 23, 1911. Serial No. 645,621.

To all whom it may concern:

Be it known that I, THOMAS SPENCER MILLER, a citizen of the United States, residing at South Orange, county of Essex, 5 and State of New Jersey, have invented certain new and useful Improvements in Cableway Button-Stops, of which the following is a specification.

My invention relates to new and useful 10 improvements in cableway button stops of that character or type employed in connection with the ropes of cableways to arrest or stop the travel of a rope, or the movement of parts traveling on or movable 15 lengthwise of a rope.

The primary object of the invention is to provide a button stop which will be capable of varied application and use wherever such a structure is desirable, but which will be 20 particularly adapted for use in connection with the ropes of cableways in which the parts travel at high speed and wherein are employed fall-rope carriers, to arrest the travel of the fall-rope carriers as the carriage or other load supporting device moves 25 lengthwise of the cableway, and to so construct the stop that the fall-rope carrier or the button stop will not be injured by the impact of a carrier against the stop.

30 A further object is to provide a button stop having associated therewith a lost motion device to yieldingly receive the impact of the fall-rope carrier and thereby cushion or break the force of the impact.

35 The invention consists in the construction and combination of parts to be fully described hereinafter, and the novelty of which will be particularly pointed out and distinctly claimed.

40 I have fully and clearly illustrated my invention in the accompanying drawings to be taken as a part of this specification, and wherein—

45 Figure 1 is a view in side elevation of a button stop constructed in accordance with my invention applied to a rope of a cableway; Fig. 2 is a longitudinal section through the button stop shown in Fig. 1.

50 Before proceeding with a detailed description of my invention I would state that it is capable of use in connection with any rope of a cableway where desired, but

I will describe the same in connection with the stop rope of a cableway, although I desire it understood that this term "stop

rope" as used hereinafter is not intended as a limitation but merely to designate the rope upon which the stop button is mounted.

Referring to the drawings by characters of reference, 1 designates a rope, as the stop 60 rope, in connection with which my invention is employed; 2 designates a member adapted to be fixed to the rope 1, and preferably in the form of a sleeve having an internal longitudinal taper bore 3 to receive 65 said rope, within which rope is located a tapered expansion pin 4, the surface of which lies parallel to the surface of said bore and the purpose of which is to expand the rope 1 into strong frictional engagement 70 with the bore to prevent longitudinal movement of the sleeve on the rope. Surrounding the rope in rear of the fixed sleeve is a thimble 5 having a reduced annular extension 6 projecting into the space between 75 the rear end of said sleeve and the stop rope, and within the said rope in rear of said thimble is an expansion block or spreader 7 to arrest the rearward movement of the sleeve and thimble should the sleeve slip 80 rearwardly on the stop rope.

The forward end of the sleeve is provided with an annular reduced portion or collar 8, the mouth of which is flared as shown in Fig. 2 to prevent wearing of the rope at 85 its entrance to the bore of the sleeve, and which extension performs a function to be presently described. The outer surface of the sleeve and thimble are tapered from the front to rear so as to form a substantially 90 continuous tapered surface as clearly shown in the drawing.

Mounted in advance of the fixed sleeve 2 is a lost motion device, preferably in the form of a sleeve 9, being oppositely tapered from an intermediate point toward its ends, as at 2^a, 2^b, and having a longitudinal internal bore 10 to receive the stop rope 1. Formed in the bore is an annular recess or counterbore 11 having shoulders 12, 13, with 100 which co-operates a projection 14 on the stop rope located within said recess, said projection being formed by expanding the cable or rope by means of a spreader block 15 clearly shown in dotted lines in Fig. 2. 105 This spreader block is of such size that when in position the diameter of the rope will be a driving fit to the bore of the sleeve so that after the spreader 15 has been inserted in the proper place in the rope the 110

movable sleeve 9 may be driven over the same until the spread portion of the rope enters the counterbore or recess 11 where it expands to form the projection described. 5 By the arrangement of the shouldered counterbore 11 and the projection 14 on the rope 1 longitudinal movement of the lost motion sleeve relative to the rope is limited in both directions. At its rear portion, or that portion directed toward the forward end of the 10 fixed sleeve 2, the lost motion sleeve 9 is provided with an enlarged bore 16 surrounding the rope, and at the base or inner end of which bore is a reduced nipple or 15 annular extension 17 surrounding the rope, and of such diameter as to leave a space 18 between this outer surface and the inner surface of said bore. Surrounding the rope and having its ends seated upon the nipples on the fixed and movable parts of the 20 button and abutting said parts at its end portions is a strong expansion spring 19 which normally holds the lost motion sleeve away from the fixed sleeve and cushions 25 any movement of said lost motion sleeve toward the fixed sleeve.

The ends of the bore 10 through the lost motion sleeve are flared in order that they will not chafe the rope passing through said 30 bore.

It is thought that the operation of the button as above described will be readily understood by any one skilled in the art, but it may be briefly stated as follows. The 35 inclined or conical surface 2^a of the member 9 is the impact surface against which the blow is delivered, given by a fall-rope carrier as the latter is removed from the carriage, or by an element against which 40 the button strikes in limiting the movement of the rope upon which the button is mounted. When the impact is delivered against the impact end of the button the element 9 is moved toward the fixed member 2, the resulting compression of the 45 spring 19 serving to break or cushion the impact and relieve both the button and the part struck thereby from the full force of the blow. The blow having been delivered, 50 the expansive force of the spring automatically returns the member 9 to normal position as shown in Figs. 1 and 2, in which position it is ready to again operate in the manner just described. The diameter of the 55 bore 16 is such that it may receive the forward end of the member 2 when the member 9 is moved rearward.

What I claim and desire to secure by Letters Patent of the United States is:—

60 1. A button stop comprising a sleeve member adapted to be fixed to a rope, a sleeve member adapted to slide on a rope both said members having spring seats, and a spring surrounding the rope and seated on said 65 seats.

2. A button stop comprising a part adapted to be fixed to a rope, and a lost motion device connected to said part.

3. A button stop comprising a part adapted to be fixed to a rope, and a cushioned lost motion device connected to said part. 70

4. A button stop comprising a part adapted to be fixed to a rope, a member adapted to slide longitudinally of a rope, 75 and a cushion between said members.

5. In a button stop, the combination of a rope, a member fixed to the rope, and another member free to slide longitudinally on the rope, and a spring interposed between 80 the two members.

6. In a button stop, in combination, a rope, a part fixed to the rope, a member movable longitudinally of the rope, and a spring between the said part and member. 85

7. In a button stop, in combination, a rope, a sleeve fixed to the rope, a sleeve movable longitudinally of the rope, and a spring between the said sleeves.

8. In a button stop, in combination, a 90 rope, a part fixed to the rope, a member movable longitudinally of the rope, a spring between the said part and member, and means for limiting the sliding movement of the movable member. 95

9. In a button stop, in combination, a rope, a part fixed to the rope, a member movable longitudinally of the rope, a spring between the said part and member, said movable member having a shoulder, and a 100 stop on the rope coöperable with the shoulder to limit sliding movement of said member.

10. In a button stop, in combination, a rope, a part fixed to the rope, a member movable longitudinally of the rope, a spring between the said part and member, said movable member having spaced shoulders, and a stop on the rope between said shoulders. 105

11. In a button stop, in combination, a 110 rope, a part fixed to the rope, a member movable longitudinally of the rope, a spring between the said part and member, said movable member having an annular shouldered recess adjacent the rope, and a 115 projection on the rope projecting into said recess.

12. In a button stop, in combination, a rope, a part fixed to the rope, a member movable longitudinally of the rope, said 120 movable member having a longitudinal bore, and a spring abutting said part and member and housed within said bore.

13. In a button stop, in combination, a rope, a part fixed to the rope, a member 125 movable longitudinally of the rope, a spring between the said part and member, and projections on said part and member upon which said spring is seated.

14. In a button stop, in combination, a 130

- rope, a part fixed to the rope, a member movable longitudinally of the rope, a spring between the said part and member, and angular projections on said part and member,
5 said projections surrounding the rope, and upon which said spring is seated.
15. In combination, a rope, a member fixed therein, a lost motion member slidably along the rope, a spring between said members, and means for limiting the movement
10 of the lost motion member away from the fixed member.

16. In combination, a rope, a member fixed to the rope, a member movable toward and away from the fixed member, and a 15 spring cushioning the movement in one direction of the movable member.

In testimony whereof I have hereunto signed my name in the presence of two subscribing witnesses.

THOMAS SPENCER MILLER.
